US00D966441S

(12) **United States Design Patent** (10) **Patent No.:** **US D966,441 S**
(45) **Date of Patent:** **** Oct. 11, 2022**

(54) **BICEPS EXERCISE DEVICE**

(71) Applicant: **BB Labs, Inc.**, Carson City, NV (US)

(72) Inventors: **Peter C. Sarna, II**, Concord, CA (US);
Roy Paul Prosise, Cedar Park, TX (US); **Cohl Thomas Prosise**, Cedar Park, TX (US); **Logan Paul Prosise**, Cedar Park, TX (US)

(73) Assignee: **BB Labs, Inc.**, Carson City, NV (US)

(**) Term: **15 Years**

(21) Appl. No.: **29/737,183**

(22) Filed: **Jun. 5, 2020**

(51) LOC (13) Cl. **21-02**

(52) U.S. Cl.

USPC **D21/680**

(57) **CLAIM**

The ornamental design for a biceps exercise device, as shown and described.

DESCRIPTION

FIG. 1 is a top plan view of an embodiment of a biceps exercise device showing my new design;
FIG. 2 is a bottom plan view thereof;
FIG. 3 is a left elevational view thereof;
FIG. 4 is a right side elevational view thereof;
FIG. 5 is a front elevational view thereof;
FIG. 6 is a rear elevational view thereof;
FIG. 7 is a top front perspective view thereof; and
FIG. 8 is a top rear perspective view thereof.
FIG. 9 is a top plan view of a second embodiment of a biceps exercise device showing my new design;
FIG. 10 is a bottom plan view thereof;
FIG. 11 is a left side elevational view thereof;
FIG. 12 is a right side elevational view thereof;
FIG. 13 is a front elevational view thereof;
FIG. 14 is a rear elevational view thereof;
FIG. 15 is a top front perspective view thereof; and,
FIG. 16 is a top rear perspective view thereof.
